UNITED STATES PATENT OFFICE.

ROBERT K. MILLARD, OF PITTSBURGH, PENNSYLVANIA.

PUZZLE.

1,380,998.

Specification of Letters Patent.

Patented June 7, 1921.

Application filed May 1, 1920. Serial No. 378,279.

To all whom it may concern:

Be it known that I, ROBERT K. MILLARD, a citizen of the United States, and a resident of Pittsburgh, in the county of Allegheny and State of Pennsylvania, have invented a new and Improved Puzzle, of which the following is a description.

The general object of my invention is to provide a sectional puzzle made up of a definite number of sections of given shapes, whereby the given task of solving the puzzle may be varied within limits to add to the interest of the puzzle.

The nature of the invention will clearly appear from the specific description following.

Reference is to be had to the accompanying drawings forming a part of this specification, it being understood that the drawings are merely illustrative of one example of the invention.

Figure 1 is a plan view of a sectional puzzle embodying elements formed in accordance with my invention and arranged to form a square;

Fig. 2 represents on a reduced scale another square formed by the same elements differently arranged;

Fig. 3 represents two figures formed from my improved sectional elements, the two figures jointly employing all the elements of the puzzle;

Fig. 4 is a plan view of another figure that may be formed from my improved puzzle by employing all the elements thereof;

Fig. 5 represents in plan and side elevation one of the elements of my improved puzzle.

In carrying out my invention I employ fifteen separate elements serving to jointly make up the sectional puzzle. Various solutions of my improved sectional puzzle are possible; the four solutions illustrated as examples will be particularly referred to in the following:

All the elements present a series of squares of equal size and adjacent squares are distinguished from each other by suitable means. In the illustrated example I distinguish a square or squares of a given element from the other square or squares of said element by a circle. The arrangement is such that when the sections are properly assembled to jointly make up a figure representing a given solution of the puzzle, squares of the respective elements will be

disposed in the complete figure in a manner that those squares similarly distinguished will alternate. The squares in each element are defined by surface lines in conjunction with the defining edges of the element.

The total of fifteen sections or elements are employed to compose the puzzle and these are respectively designated in the assemblage of Fig. 1 by the numerals 11 to 25, inclusive.

Four L-shaped elements numbered 11, 12, 15 and 19 each presenting three squares are employed, some of said elements presenting two squares similarly distinguished (by the circle for example) and a single square otherwise distinguished as by leaving the same plain, while in others of the said four L-shaped elements two squares remain plain and unmarked while the third is distinguished by the particular means adopted, such as the circle. The other elements of the puzzle are as follows: An L-shaped element presenting five squares, of which four are in line; one element, 22, presenting five squares of which four are disposed in the form of a T and one at one end of the T-head and at the opposite side from that square constituting the shank of the T; one element, 20, presenting four squares arranged in the form of a square, and a fifth square at one side of one of the said four squares; two elements, 13 and 14, of T-shape presenting four squares, that is, three in the head of the T, and one representing the shank of the T; one element, 17, presenting six squares of which four are in a row, and two at the sides of the two intermediate squares in said row of four; one element, 24, presenting four squares in a row and the fifth square at a side of one of the squares and disposed next to an end square; three elements, 16, 21, and 25, presenting four squares disposed in two overlapping rows of two squares each; and finally, one element 23 presenting four squares in a row and two squares at one side of said row, said two squares being spaced the distance of one square and one of said two squares being adjacent to an end of said row.

In Fig. 2 the total number of elements (11 to 25) is employed to form a square but having the elements therein differently arranged from Fig. 1.

A third example of a solution of the puzzle is afforded by Fig. 3, wherein two figures are shown, the one (at the left of Fig. 3)

made up of the elements 15, (or 11); 16, (or 21); 18; 19, (or 12); 22; and 25 (or 21); while the figure at the right of Fig. 3 is similar to that at the left except that it has 5 two additional and longer rows of squares at the center, said figure at the right of Fig. 3 being made up of the elements as follows: 11 (or 15); 12; 13; 14; 17; 20; 21; 23 and 24.

10 In Fig. 4 a further example is given of a figure employing all the elements (11 to 25).

Fig. 5 is given to show one of the sectional elements to wit; No. 25, which, as stated, 15 corresponds with 16 and 21 in shape.

I would state in conclusion that while the illustrated example constitutes a practical embodiment of my invention, I do not limit myself strictly to the exact details 20 illustrated herein, since manifestly the same can be considerably varied without departure from the spirit of the invention as defined in the appended claim.

Having thus described my invention, I 25 claim:

A sectional puzzle comprising fifteen elements each presenting a plurality of squares of equal size and defined jointly by surface lines and the marginal edges of the respective elements, adjacent squares being distinguished, said elements presenting members

and surface squares positioned to variously receive different members and squares of others of said elements in a variety of distinctive assemblages, said elements comprising the following to wit; four L-shaped elements each presenting three squares; three elements each presenting four squares disposed in two overlapping rows of two squares each; two elements of T-shape presenting four squares; one L-shaped element presenting five squares of which four are in line; one element presenting five squares of which four are disposed as a T and one at one end of the T-head and at the opposite 45 side from that square constituting the shank of the T; one element presenting four squares arranged as a square, and a fifth square at one side of one of the said four squares; one element presenting six squares 50 of which four are in a row and two at one side of said row alongside the two intermediate squares in said row; one element presenting four squares in a row and a fifth square at a side of one of the squares disposed next to an end square in said row; and one element presenting four squares in a row and two squares at one side of the row, said two squares being spaced the distance of one square and one of the two being 55 adjacent to an end of said row.

ROBERT K. MILLARD.
